BOOK DESIGN

Richard A. Kjarsgaard, Reseda, Calif., assignor to
Patrick L. Schmidt and David A. Hill, both of Marina
Del Rey, Calif.

Filed Aug. 7, 1972, Ser. No. 278,435

Term of patent 14 years

Int. Cl. D19—04

U.S. Cl. D19—26

FIG. 1 is a perspective view of a book design showing my new design;

FIG. 2 is a front elevational view;

FIG. 3 is a right side elevational view;

FIG. 4 is a rear elevational view;

FIG. 5 is a left side elevational view;

FIG. 6 is a bottom plan view; and

FIG. 7 is a top plan view.

I claim:

The ornamental design for a book design, as shown and described.
